DESIGN FOR A DISPENSER FOR COTTON, PAPER TISSUES OR THE LIKE

Anthony A. Sambito, Leominster, Mass.

Application December 22, 1948, Serial No. 150,313

Term of patent 7 years

(Cl. D52—2)

To all whom it may concern:

Be it known that I, Anthony A. Sambito, a citizen of the United States, residing at Leominster, in the county of Worcester and State of Massachusetts, have invented a new, original, and ornamental Design for Dispenser for Cotton, Paper Tissues or the like, of which the following is a specification, reference being had to the accompanying drawing, forming part thereof.

Fig. 1 is a view in front elevation; and Fig. 2 is a view in side elevation of a dispenser for cotton, paper tissues or the like, showing my new design.

I claim:

The ornamental design for a dispenser for cotton, paper tissues or the like, as shown.

ANTHONY A. SAMBITO.
